UNITED STATES PATENT OFFICE.

DANIEL J. RYAN AND LOUIS J. FELTES, OF CLEVELAND, OHIO.

PROCESS OF AND APPARATUS FOR POURING METAL.

1,426,110.

Specification of Letters Patent. Patented Aug. 15, 1922.

Application filed August 29, 1917. Serial No. 188,761.

To all whom it may concern:

Be it known that we, DANIEL J. RYAN and LOUIS J. FELTES, citizens of the United States, residing at Cleveland, in the county 5 of Cuyahoga and State of Ohio, have invented certain new and useful Improvements in and Relating to Processes of and Apparatus for Pouring Metal, of which the following is a specification.

10. This invention relates to process of and apparatus for pouring molten metal into molds.

One object of the invention is to provide an improved pouring apparatus adapted to 15 prevent slag and foreign matter from entering the mold cavity.

Another object of the invention is to provide a metal pouring apparatus in which the metal is so controlled during pouring 20 that the slag and foreign matter is collected and prevented from passing with the molten metal into the mold cavity.

Another object of the invention is to provide improved means for readily and quickly 25 pouring molten metal into a mold cavity in a uniform and steady manner without danger of damaging the walls of the mold or sprue.

Another object of the invention is to provide an improved pouring apparatus in 30 which one or more molds can be poured in a simple, rapid and economical manner.

Another object of the invention is to provide improved pouring apparatus adapted 35 to discharge the molten metal into the mold cavity from a point below the upper surface of the charge of metal which is being poured.

Another object of the invention is to provide novel means for discharging the molten metal from the ladle, and guiding and controlling the metal to the mold cavity, whereby the pouring operation is simplified and labor and time saved.

45. Another object of the invention is to provide an improved pouring apparatus in which the metal holder is mounted on a carriage that may be readily and quickly moved over the molds with the metal holder or 50 ladle in position immediately above the pouring basin of the mold.

Another object of the invention is to pro-

vide an improved pouring apparatus in which the metal holder is tiltably mounted upon a support with means, which automatically lock the metal holder when tilted in the pouring position.

Another object of the invention is to provide means for measuring the metal placed in the metal holder and its discharge therefrom, either or both, for pouring.

Another object of the invention is to provide an improved process of pouring metal, whereby slag and foreign matter are collected and the molten metal is guided and controlled while being poured.

These and other objects of the invention will be obvious to those skilled in the art, to which our invention relates, from the following description:

For the purpose of illustration we have, in the accompanying drawings, shown and herein described one form of apparatus embodying our invention.

Fig. 1 is a side elevation of a pouring apparatus embodying our invention and a mold, the pouring apparatus being in position relative to the mold for pouring.

Fig. 1^a is a fragmentary view illustrating a construction embodying a slightly modified form of the invention.

Fig. 2 is a top plan view of the pouring apparatus.

Fig. 2^a is a perspective view of the metal controlling device.

Fig. 3 is an end elevation of the pouring apparatus.

Fig. 4 is a fragmentary sectional view on the line 4-4 of Fig. 2.

Fig. 5 is a fragmentary sectional view on the line 4-4 of Fig. 2, showing the metal holder or ladle tilted into position for pouring.

Fig. 6 is a fragmentary end elevation illustrating details of construction.

Fig. 7 is a fragmentary side elevation of the apparatus.

Figs. 8, 9 and 10 are views corresponding substantially to Figs. 2, 4 and 6, but illustrating a slightly modified form of construction.

Figs. 11 and 12 are top plan and end elevational views, respectively, illustrating another modification of the construction.

Figs. 13, 14, 15 and 16 are detail sectional views of the construction shown in Figs. 11 and 12, on the line XVI—XVI of Fig. 12.

5 In the drawings, 1 indicates as an entirety a support or frame preferably comprising a pair of skeleton side members 1^a, and a pair of cross members 1^b. The side and cross members 1^a, 1^b, are rigidly connected 10 together in any well known manner, as by bolts 1^c. Each side member 1^a depends downwardly and is preferably provided at its lower end with spaced arms, as shown at 1^d. The free ends of the arms 1^d are 15 provided with aligned bearings 1^e to receive a shaft or shafts on each of which is mounted a wheel 2. The wheels 2 permit the support 1 to be moved from place to place to position the pouring apparatus in 20 co-operative relationship with the pouring basin or basins *a* of a mold A. For convenience, the support or frame 1 will be hereinafter referred to as a carriage. We 25 preferably provide the carriage at one side with two wheels 2 and at the other side with one wheel 2, so that the carriage will readily accommodate itself to uneven surfaces in the floor over which it is to be moved. The 30 cross members 1^b of the carriage are connected to the side members 1^a at a suitable distance above the floor line to permit the carriage to be rolled over and straddle a mold A, as illustrated in Fig. 1. At their 35 central portions the cross members 1^b may be cut out or shaped, as shown at 1^{b'}, so that they will clear all parts or attachments of the mold A, such as clamps *a'*. As the carriage 1 is shaped and constructed to be moved over or straddle a mold A, the latter 40 can be arranged side by side in rows and the carriage successively moved to pouring positions over the molds in each row and thereby facilitate the pouring thereof. If 45 desired, the floor may be provided at either side of the row of molds with tracks, as shown at B in Fig. 1^a; in that event, the wheels 2 are flanged in any well known manner to travel on the tracks B. When so constructed, the carriage 1 may be more 50 readily moved and guided from a position for pouring one mold to a position for pouring the next mold.

3 indicates a buffer carried by the inner arms 1^d of each upright member 1^a. Each 55 buffer 3 preferably comprises a board or plate, the opposite ends of which are beveled (Fig. 2). The buffer 3 may be secured to the adjacent arms 1^d in any well known manner. When the wheels 2 engage with the floor and are not guided, the buffers 3 will keep the carriage 1 from 60 engaging projecting parts of the mold, such as the projecting parts *a'*, as it is being moved from one mold to the other.

65 4 indicates as an entirety a metal holder

or ladle adapted to receive a charge or charges of molten metal from a suitable source of supply and discharge it in the manner hereinafter described. The holder 70 4 may be of any desired shape. It is preferably arranged in a horizontal position and rotatably supported at its opposite side or end walls 4^x by the side members 1^a. This construction permits the holder to be elongated in the direction of the axis on 75 which it swings, to hold the desired quantity of metal as well as simultaneously to discharge metal into a plurality of mold basins, without enlargement of the holder vertically. The walls of the ladle 4 are 80 preferably lined with fire clay or other suitable material 4^x, which may be secured to the walls of the ladle through openings 4^{x'} formed therein. For illustrative purposes, we have shown two forms of holders, one 85 form being shown in Figs. 1, 2, 3, 4 and 5, and the other form being shown in Figs. 8, 9 and 10. In this latter form, the holder is cylindrical in cross section. It is formed with an opening, as shown at 4' to permit 90 filling with molten metal. The opening 4' preferably extends from end to end of the holder. As the wall of the holder is concentric to its axis, it may be readily rotated, without changing its center of gravity or 95 the center of gravity of the metal contained in the holder, in opposite directions to effect successive pouring operations. The opening 4' is formed in the upper portion of the holder, but substantially rearward of a vertical plane cutting the axis of the holder when the latter is in normal position. When so constructed, the holder may be rotated a quarter turn or more without danger of 100 the metal spilling from the opening 4'. 105

At 5 the holder 4 is formed with an opening through which the molten metal is discharged when the ladle is tilted into its discharging position (see Fig. 5).

The opening 5 is arranged above the level 110 of the molten metal in the ladle 4, but when the latter is tilted for pouring purposes, the opening becomes positioned at or substantially at the lowest part of the body of metal. As a result, the metal discharged into the 115 mold is always taken from a point below its upper surface; the discharged metal is at all times clean or free of all slag and foreign matter, which is in, or collects on top of, the charge of metal in the holder.

We preferably provide as many openings 5 as there are pouring basins *a* in each mold or a plurality of molds to be poured, so that the molten metal can be simultaneously poured into all the basins. In the illustrated embodiment of our invention we have shown a mold A having two pouring basins *a* and therefore the ladle 4 is provided with two discharge openings 5 suitably spaced from each other. The openings 5 may be 120 125 130

formed in the holder at any desired point above the bottom of the holder when the latter is in normal position (Figs. 4 and 10). The ladle 4 is filled with a sufficient quantity 5 of metal to complete one or more pouring operations, as desired. The openings 5 may be arranged at such point as to be slightly above the surface of that quantity of metal which the ladle is intended to hold or receive 10 at one time, so that the operative can fill the ladle 4 with molten metal until the metal rises therein to or slightly below the lower edge of the openings 5. When the openings 5 are arranged in this manner, 15 the operative can readily determine when the ladle has been filled with the predetermined quantity.

In the form of construction shown in 20 Figs. 1, 2, 3, 4, and 5, the ladle 4 is provided with a bottom wall 4^a, a rear wall 4^b, and a front wall 4^d. The front wall 4^d is provided with an upwardly and inwardly extending wall 4^{d'} which co-operates with the wall 4^a and bottom wall 4^a to hold the molten metal 25 within the ladle 4 when the latter is tilted to the position shown in Fig. 5. The walls 4^d and 4^{d'} are preferably integrally formed along a line which cuts the axes of the openings 5. When so arranged and the ladle 4 30 is tilted for pouring, the openings 5 will be at the lowest point thereof. If desired, the front walls 4^d, 4^{d'} of the holder 4 may be inclined downwardly from the center of the holder toward either end, as shown in Fig. 35 2, to insure the discharge of the metal through the openings 5.

6 indicates trunnions, which are preferably formed integrally with and extend laterally from the opposite end walls 4^c of the 40 ladle 4. The trunnions 6 may rotatably bear upon pairs of spaced rollers 7, 7, one pair for each trunnion, which serve as supporting devices 7' for the trunnions 6 upon the carriage 1. The supporting devices are 45 preferably adjustable vertically, so that the ladle 4 can be arranged in a horizontal position irrespective of the irregularities or inclinations of the floor or rails on which the carriage 1 moves. The supporting devices 50 7' are arranged at either side of the carriage 1, the devices at one side being similar in construction to those at the opposite side. Accordingly, we will describe the devices at one side of the carriage 1 only. Of these 55 devices, 7^a indicates a plate slidably mounted between a pair of guide walls 8 and a plate 8^a preferably formed integrally with and extending upwardly from the adjacent side member 1^a. At 7^b the plate 7^a is formed 60 with an elongated slot through which a bolt 8^b extends. The bolt 8^b extends through an opening formed in the plate 8^a and is provided with a nut 8^c which serves to hold the plate 7^a thereagainst, but permits the plate 65 7^a to slide upwardly and downwardly. At

its upper end the plate 7^a is provided with a pair of stud shafts 7^{a'} on which the rollers 7 are loosely mounted. 9 indicates a lug which may be provided on the adjacent side member 1^a and formed with a screw-threaded 70 opening to receive a screw 9^a. The screw 9^a preferably carries at its lower end a hand or crank wheel 9^b, whereby the screw may be rotated in either direction. The upper or free end of the screw 9^a bears against the 75 plate 7^a or a projection 7^c carried thereby and operates to support the plate in any position to which it may be adjusted by the rotation of the screw 9^a. As the screws 9^a may be turned in either direction independently, the supporting devices 7' at either side of the ladle 4 can be operated to support the latter in a horizontal position, irrespective of the plane of the floor or tracks on which the carriage 1 rests. 80

10 indicates a device, such as a hand wheel, which may be connected to the outer or free end of either trunnion 6, for the purpose of tilting the ladle 4 on its trunnions. The device 10 is provided with a socket member 10^a in which is formed a socket 10^{a'} to receive the outer end of the adjacent trunnion 6. The free end of each trunnion 6 is of irregular shape and the socket 10^{a'} is of corresponding shape, so that the socket member 10^a can be readily connected to a trunnion 6 and rotary movement imparted thereto. We preferably line the socket with a suitable heat insulating material so as to prevent the heat from the metal imparted to the walls of the ladle 4 and trunnion 6, by reason of the heat conductivities thereof, from affecting the device 10 which has to be grasped by an operative. The socket member 10^a may be 95 rigidly secured to the free end of the trunnion 6 by a set screw 10^b. 100

The ladle 4 is preferably maintained in its metal receiving position, as shown in Figs. 4 and 10, by means of a weight 11 adjustably mounted on an arm 12, which extends laterally from that side of the ladle opposite to the side in which the openings 5 are formed. The inner end of the arm 12 is connected in any desired manner to one of the trunnions 6, preferably that trunnion 6 remote from the trunnion to which the operating device 10 is secured; the arm may be fixed to the adjacent trunnion by means of a set screw 12^a. The weight 11 may be 110 adjustably secured to the arm 12 by a set screw 11^a. The weight carrying arm 12, being secured to the adjacent trunnion 6, swings therewith when the ladle 4 is tilted; as a result of this construction and arrangement, the weight 11 tends to return the ladle to and maintain it in its metal receiving position. 125

13 indicates devices which stop the swinging movement of the ladle 4 on the trun- 130

nions 6 in either direction. The devices 13 are so disposed that they will engage with the rollers 7 when the ladle is moved in one direction or the other, as shown in Figs. 3, 5 and 9. The stopping devices preferably comprise a plate 13^a provided with a pair of oppositely disposed arms 13^b, 13^{b'}. The plate 13^a is secured to one of the trunnions 6 in any desired manner. The arms 13^b, 10 13^{b'}, are constructed and arranged so that the stop arm 13^{b'} will engage with the adjacent roller 7 when the ladle 4 is in its metal receiving position (Figs. 4 and 9) to prevent movement thereof rearwardly, and 15 the stop 13^b will engage with the adjacent roller 7 when the ladle 4 is tilted into its metal discharging position (Figs. 5 and 6) to discharge the metal from the ladle through the openings 5. From the above 20 description it will be seen that the rollers 7 serve as engaging members for the stop arms 13^b, 13^{b'}, and limit the tilting or swinging movement of the ladle 4 in one direction under the influence of the weight 11 25 and to limit the tilting or swinging movement of the ladle 4 in the opposite direction by the operation of the operating device 10.

We preferably provide means, indicated 30 as an entirety at 14, for automatically locking the ladle in its metal discharging position, so that after it has been moved into position to discharge the molten metal, the operative will be relieved from holding the 35 ladle 4 during the pouring operation, and may temporarily move away to avoid the heat from the metal.

Of these locking means, 14^a indicates a lock and release member preferably pivoted 40 upon one of the adjustable plates 7^a, so as to be moved therewith whenever the plate is adjusted vertically. The lock and release device 14^a preferably consists of a bell crank lever one arm 14^{a'} of which is adapted to 45 move into the path of movement of a shoulder 14^b projecting laterally from a collar 14^c fixed in any well known manner to the adjacent trunnion 6. The other arm 14^{a'} of the lever 14^a serves as a weight to swing 50 the arm 14^{a'} inwardly into the path of movement of the shoulder 14^b. When the ladle 4 is in its metal receiving position, the lock and release member 14^a and shoulder 14^b are arranged as shown in Figs. 3 and 55 9, but when the ladle 4 is tilted the shoulder rides the arm 14^{a'} until it passes its free end, whereupon the arm 14^{a'} swings inwardly to the position shown in Fig. 6, below or in the path of movement of the shoulder 14^b. The ladle is then locked or 60 prevented from swinging back to the metal receiving position. To release the lock and release member 14^a, the operative lifts the arm 14^{a'} far enough to cause the disengagement of the arm 14^{a'} from the shoulder 14^b, 65

whereupon the ladle 4 will swing back to the metal receiving position under the influence of the weight 11.

15 indicates a device which is arranged between or intermediate the ladle 4 and each basin *a* or mold cavity for the mold A. The principal functions of the device 15 are (1) to control the flow of the metal from the ladle 4 to the mold basin *a* or mold cavity, while the ladle is moving from its metal receiving position to its metal discharging or pouring position, (2) to prevent the molten metal from flowing under pressure or head direct to the mold basin or mold cavity, but permit a steady and uniform flow of the metal thereto, from a discharge orifice or opening which is relatively close to the mold basin or mold cavity, and (3) to provide a receptacle which permits the metal flowing to the mold basin *a* or mold cavity to accumulate therein so that slag and other foreign matter may collect on or rise to the top of the metal and not flow into the mold cavity, but will either cling to the walls of the basin or follow the last portion of the metal passing through the discharge orifice of the basin. The metal controlling devices 15 are shaped in any desired manner to receive and hold a relatively large quantity of the metal which is being poured. Each device 15 comprises a receiver 15' in which the metal, as it flows from the holder 4 to the mold cavity, accumulates, and a deflecting or guide wall 15^b to guide and direct the metal downwardly 100 into the receiver. The devices 15 are preferably carried by the carriage 1, being preferably supported at their opposite ends on the cross members 1^b. For this purpose, each device 15 may be provided at its opposite 105 ends with brackets 15^a which fit suitably shaped recesses 1^{b2} formed in the cross members 1^b. The recesses 1^{b2} in one cross member 1^b are aligned with the recesses in the other cross member. The brackets 15^a and 110 recesses 1^{b2} are so shaped and correlated as to form a suitable connection between the cross members and the device 15 to support the latter in co-operative relationship to the adjacent discharge opening in the ladle 4. 115

The guide wall 15^b is arranged at that end of the device 15 adjacent the side wall of the ladle in which the pouring openings 5 are formed. The guide wall 15^b extends upwardly so as to catch and divert, guide or direct the metal which flows out of the adjacent opening 5 during the first part of the tilting movement of the ladle 4, downwardly into the receiver 15'. At 15^c the bottom of the receiver 15' is formed with a 120 discharge opening through which the metal flows to the adjacent basin *a*. By this construction, the metal is discharged into the mold basin *a* from a point below the surface of the metal in the receiver 15'. The 125 130

size of the opening 15^e is preferably proportioned relative to the size of the opening 5 so that the metal cannot flow from the receiver 15' too rapidly, but will be caused to accumulate therein to permit slag and foreign matter to rise to the surface of the metal. The opening 15^e is preferably arranged to direct the metal into the adjacent basin *a* at a point remote from the sprue 10 C. Each receiver 15' may be lined with suitable heat resisting material, as shown.

Each mold basin *a* is preferably provided with a skim gate D, the opening *d* through which is preferably arranged to discharge the metal from the basin *a* at a point below its upper or exposed surface. Prior to each pouring operation we prefer to close each gate opening *d* by a piece of tin. The tin *d'* serves to retard the flow of the metal 15 from the basin *a* until it melts and opens the passage *d*. This causes the metal to accumulate in the basin *a* and thus insures that any slag or foreign matter, which has not 20 been eliminated from the metal or which 25 may form thereon, will be collected on top of the metal and be prevented from passing into the sprue C.

The openings 5 and 15^e are also preferably formed of a size which will properly 30 control the flow of metal according to the gating in the mold. When it is necessary to change the apparatus for pouring molds having a different gating, the ladle 4 and basins 15 can be removed and a ladle and 35 basins having the proper size openings substituted therefor.

In operation, the ladle 4 is first filled with the desired quantity of metal, this being 40 preferably controlled by arranging the openings 5 at a suitable height above the bottom or lowest point of the ladle. The operative then grasps the wheel 10 and tilts the ladle 4 to the position shown in Fig. 5. This operation causes the openings 5 to 45 be arranged at or substantially at the lowest part of the body of metal and therefore permits the discharge of the metal at a point below its upper surface, that portion of the metal constituting its upper surface and the slag and foreign matter thereon either flowing through the openings last 50 or clinging to the walls of the ladle. From the ladle 4, the metal flows into the receivers 15', where it collects and rises to 55 permit any slag and foreign matter which may pass through the openings 5 or which may form on the metal while in the receivers 15', to accumulate on or rise to the top of the metal and not flow into the mold cavity. From the receivers 15' the metal 60 flows through the openings 15^e into the basins *a* where it again collects or accumulates to permit any slag and foreign matter, which may have passed through the openings 15^e, to collect on and rise to the top

of the metal in the basins *a*. From the basins *a* the metal flows through the openings *d* in the skim gates D, which openings being below the surface of the metal in the basins *a*, permit only metal from which all 70 slag and foreign matter has been eliminated, to enter the mold sprues.

16 indicates a shield the purpose of which is to protect the operatives from the heat radiating from the molten metal, which is 75 in the ladle 4 or is being poured therefrom. The shield 16 is supported in any well known manner on the carriage 1. The shield 16 preferably comprises a front wall 16^a arranged in front of the ladle 4, and 80 side walls 16^b. At either end, the front wall 16^a is cut away, as shown at 16^c, to clear the metal controlling devices 15 or 85 walls 15^b thereof and to permit the operatives to look through the openings 16^c and view the rotative movement of the ladle and the discharge of the metal from the openings 5 thereof.

From the foregoing description it will be seen that we first discharge the metal from 90 a ladle or holder at a point below its upper or exposed surface therein, direct the metal downwardly and cause it to accumulate and rise in a receiver, thereby preventing the metal from acquiring any head or pressure 95 due to its discharge, and permitting slag and foreign matter in or which may collect in the metal to rise to the surface thereof; that from the receiver we again discharge the metal at a point below its upper or exposed surface into a basin and cause it to 100 again accumulate and rise therein, thereby again preventing the metal from acquiring any head or pressure due to its discharge into the said basin and permitting slag and 105 foreign matter in or which may collect in the metal to rise to the surface thereof; and that from this latter basin we finally discharge the metal at a point below its exposed surface into the sprue of the mold. 110

It will also be seen that in carrying out our process we provide a plurality of holders for the metal and discharge the metal from one holder to another before it enters the mold sprue so that the metal 115 is sufficiently stirred to give ample opportunity for all foreign matter to be collected and eliminated from the metal by the time it reaches the mold sprue. At the same time the metal flows substantially continuously 120 from the ladle 4 to the sprue of the mold and is so controlled that substantially all pressure or head due to its height of fall from the holder 4 is prevented. Furthermore, we are enabled, by our apparatus for 125 and process of pouring metal, to avoid the necessity of using skimming gates, discharge plugs or valves; furthermore, we are enabled to use pouring basins of relatively small size and to completely fill the mold cavities 130

with metal which has been clarified of slag and foreign matter so that uniform and perfect castings are produced.

We prefer to provide the apparatus with a measuring mechanism, indicated as an entirety at 17, in Figs. 11 and 12 to indicate when a (1) predetermined quantity of metal is placed in the holder 4, and (2) predetermined quantity of metal is discharged therefrom. The measuring mechanism 17 preferably comprises a rising and falling support 17^a, which is counter-balanced by a weight 17^b, the adjustment of which determines when, due to the weight of the metal in the holder 4, the support rises or falls. When the apparatus is constructed with a measuring and indicating mechanism 17, we prefer to trunnion the holder 4 on the plates 7^a as already described, in which event the latter serve as the rising and falling support 17^a. In this form of construction we prefer to provide anti-friction rollers 17^c between the plates 7^a and the guide walls 8. The rollers 17^c may be flanged to maintain the plates vertically and in sliding engagement with the wall 8^a. 17^d indicates a lever or beam pivoted at 17^d in any well known manner—but preferably by anti-friction means—upon each side member 1^a. The inner end 17^e of each lever 17^d has pivotal connection with the adjacent plate 7^a to support it; the outer end 17^f of the lever 17^d carries the weight 17^b and is graduated in any suitable manner to readily indicate different positions of adjustment for the weight. The indications may consist of notches 18 which receive the supporting link of the weight 17^b. 17^b indicates a supplemental weight preferably detachably connected to the free end of the lever arm 17^f.

The pivotal connection between each lever arm 17^e and the adjacent plate 7^a is preferably of an adjustable type to permit leveling of the holder 4 in the manner already described. For this purpose, the lever arm 17^e is bifurcated to receive and support on pivots 19 a block 19^a. The block 19^a is formed with a screw-threaded opening to receive an adjusting screw 9^a the upper end 50 of which engages the plate 7^a or the lug 7^c thereon. At its lower end the screw 9^a preferably carries a crank wheel 9^b.

The operation of pouring molds, when the apparatus is equipped with mechanism for indicating the charge or charges of metal received by and discharged from the holder 4, is as follows: The lever 17^d is shown as provided with five notches. This will permit the holder 4 to be filled with sufficient metal for pouring five molds. The weight 17^b is placed in the outermost notch, then molten metal is poured into the holder 4 until the weight thereof overcomes the weight 17^b and causes the support 17^a to drop or fall, this movement being arrested by engagement of

the lever 17^d with a suitable stop 20 projecting laterally from some part of the carriage 1. The movement of the support 17^a downwardly or the outer end of the lever 17^d upwardly indicates that the holder 4 contains the desired quantity of metal; accordingly the supply thereof is cut off. The apparatus is moved into proper position for pouring a mold and the weight 17^b moved or adjusted to the next notch in the lever arm 17^d. The holder 4 is now rotated on its trunnions, as already described, to discharge the metal and pour the adjacent mold. The holder 4 is maintained in its pouring position until sufficient metal runs or flows out of it to permit the weight 17^b to overbalance that portion of the metal still remaining in the holder 4, whereupon the weight 17^b will cause the support 17^a to rise, this movement being arrested by a suitable stop 21 arranged in the path of movement of the lever arm 17^d and indicating to the operative that one charge of metal, or an amount sufficient to fill one mold has been discharged from the holder 4. The operative thereupon rotates the holder back to normal position.

The apparatus is now moved to the position for pouring the second mold. The weight 17^b is adjusted to the next or succeeding notch, which causes the support 17^a to drop to its lowermost position. The holder 4 is now rotated to the pouring position and maintained therein until enough metal flows out to permit the weight 17^b to overbalance that remaining. When this condition is reached the support 17^a rises and thus indicates to the operative that another charge of metal has been poured.

These operations are repeated until all the charges of metal have been poured. The weight 17^b is then readjusted to the outermost notch and the holder is then refilled, in the manner already described. The holder 4 may be made to hold any quantity of metal desired and the lever 17^d may be graduated to indicate charges of metal of different amounts or sizes according to the quantity of metal required for each mold. Furthermore, the successively discharged charges do not have to be of the same size, but can be varied simply by varying the adjustment of the weight 17^b along the lever 17^d.

22 indicates a supplemental set of wheels which permits the carriage 1 readily to be moved at an angle to the direction in which it may be moved by or upon the set of wheels 2. The carriage 1 is constructed to permit it to be moved over or alongside of a series of molds arranged side by side in a row. To permit in a convenient manner, without requiring considerable room and labor, the movement of the carriage from one row of molds to another row of molds, we provide the wheels 22 and arrange their 130

axes at right angles to the axes of the wheels 2 and interpose between either one of the sets of wheels 2 and 22, but preferably the latter, raising and lowering mechanism 23 for causing relative movement between such set of wheels and the carriage 1, whereby the latter may be supported by either set of wheels. Where the wheels 2 are mounted on tracks, the wheels 22 and raising and lowering mechanism form a convenient means for shifting the carriage 1 from one track to another track.

Each wheel 22 is supported at the lower end of a leg 22^a which is slidably mounted 15 between the connecting members of the adjacent arms 1^a. Each leg 22^a is preferably formed with an elongated slot 22^b to receive a pin 1^c that is carried by the adjacent connecting members 1^{dx}. At its upper end the leg 22^a is bifurcated at 22^d, the bifurcations being disposed upon opposite sides of and guided by a shaft 23^a, which forms one element of the raising and lowering mechanism 23. Each shaft 23^a is mounted in bearings 23^b provided on the adjacent side members 1^a. 23^d indicates collars, detachably connected to each shaft 23^a and arranged by engagement with the bearings 23^b to prevent endwise movement of the shaft. At 25 either or both ends, each shaft 23^a is provided with a wheel 23^c by which the shaft may be rotated. 24 indicates toggle devices interposed between each shaft 23^a and the adjacent leg or legs 22^a. Of these devices, 24^a indicates an arm fixed at its inner end in any well known manner to the shaft 23^a. At its outer end, the arm 24^a is pivotally connected to one end of a link 24^b; the opposite end of the link 24^b is in turn pivotally connected to the adjacent leg 22^a. As 30 shown in Fig. 12, the upper end of each leg 22^a is constructed to provide two sets of bifurcations 22^d between which the adjacent toggle devices 24 are arranged. In Fig. 13 we have shown in detail the wheel 22 and leg 22^a therefor in normal position, that is, with the carriage 1 lowered and supported on the wheels 2. If, now, the shaft 23^a is rotated in an anti-clockwise direction, 35 as viewed in Fig. 14, the arm 24^a, acting through the link 24^b, will slide the leg 22^a downwardly until the wheel 22 carried thereby engages the floor; thereafter the continued movement of the shaft 23^a and arm 24^a to the positions shown in Figs. 15, 16 and 12, reacting through the leg 22^a and wheel 22 and the engagement of the latter with the floor, will elevate the carriage 1, as 40 shown in Fig. 12 and cause it to be supported by the wheel 22. Each link 24^b is preferably bent to form a recess 25 which lies over the adjacent shaft 23^a, when the parts are in the position shown in Fig. 13, thereby serving to support the leg in ele-

vated position. On that side of the link 65 24^b opposite to the recess 25, the link is provided with a lug 26 which engages with the shaft 23^a after the pivot connection 24^a has been moved to a position beyond its "dead center" position, as shown in Fig. 16, such lug 26 and its engagement with the shaft 23^a serving to lock the toggle devices in this position. We prefer to provide each toggle device 24 with two arms 24^a and two pivot lugs 24^b and arrange the link 24^b between them in order, among other reasons, that the power to raise and lower the carriage 1 may be effectively applied through these parts.

As will be understood from Fig. 12, we mount two wheels 22 on that side member 1^a carrying one wheel 2, one at either side of the latter, and mount one wheel 22 between the two wheels 2 carried by the other side member 1^a.

Our apparatus and process of pouring is 85 particularly advantageous because it materially decreases the time of pouring and labor costs therefor, both in number of men and the skilled character of the labor required. Our invention enables a plurality 90 of molds to be poured in a relatively short period of time, since less labor is required to position the apparatus for each pouring operation. Since the construction of the apparatus is such as to properly control and 95 discharge the metal and to eliminate the slag and foreign matter therefrom, the operatives are relieved from removing the latter or giving special attention to the pouring of the metal once the apparatus is properly positioned.

To those skilled in the art of making apparatus of the class described, many alterations in construction and widely differing embodiments and applications of our 105 invention will suggest themselves, without departing from the spirit and scope thereof. Our disclosures and the description herein are purely illustrative, and are not intended to be in any sense limiting.

For example, the carriage may be supported upon the floor or a track at one side of a mold and moved alongside thereof and adjoining molds to position the holder for pouring.

What we claim is:

1. In mechanism of the class described, the combination of a support, and a metal holder trunnioned on said support and adapted to be moved from a normal position 120 to a discharging position, one side wall of said holder being formed with a discharge opening which is arranged above the level of the metal when the holder is in normal position but is moved to a position below such level when said holder is tilted, the upper portion of said side wall extending inwardly, whereby it operates to hold the

metal when the holder is tilted to its discharging position.

2. In mechanism of the class described, the combination of a support, and a metal holder trunnioned on said support and adapted to be moved from a normal position to a discharging position, the upper portion of one side wall of said holder extending inwardly, whereby it operates to hold the metal when the holder is moved on its trunnions to the discharging position, the said mentioned side wall being formed with a discharge opening at the point of connection of the lower and upper portions thereof, whereby said opening is disposed at the lowest point of said holder when the latter is tilted.

3. In mechanism of the class described, the combination of a support, and a metal holder trunnioned thereon, the upper portion of one side wall of the holder extending inwardly from a point above the level of the charge of metal in said holder, and co-operating with the lower portion of said side wall to hold the metal when said holder is tilted and formed with a discharge opening at the point of connection of the lower and upper portions of said wall.

4. In mechanism of the class described, the combination of a support, and a holder for metal having side walls of curvilinear shape and supported at its opposite ends on trunnions disposed in line with the axis of said side walls, whereby the holder may occupy a filling position and a discharging position without changing its center of gravity, one side wall of said holder being formed with a discharge opening disposed above the level of the metal when the holder is filled and in the filling position and disposed at the lowest part of said holder below the level of the metal when said holder is in the discharging position.

5. In mechanism of the class described, the combination with a mold, of a pair of spaced members arranged to be positioned at opposite sides of said mold, and a metal holder adapted to receive metal trunnioned on said members, one side wall of said holder being formed with an opening between its upper free edge and the level of the metal when the holder is in normal or filling position and disposed below the level of the metal when said holder is tilted to its discharging position.

6. In mechanism of the class described, the combination with a mold, of a pair of spaced members arranged to be positioned at opposite sides of said mold, a metal holder adapted to receive metal trunnioned on said members, one side wall of said holder being formed with an opening between its upper free edge and the level of the metal when the holder is in normal or filling position and disposed below the level of the

metal when said holder is tilted to its discharging position, and means for vertically adjusting one of said trunnions on the adjacent member.

7. In mechanism of the class described, the combination with a mold, of a frame comprising a pair of spaced members connected at their upper ends by a cross member, whereby the frame may straddle the mold and be moved thereover, a metal holder trunnioned on said frame and movable from a position for receiving metal to a position for discharging it, one side wall of said holder being formed with a discharge opening arranged above the surface of the metal when the holder is in metal receiving position and arranged below the surface of the metal in operative relationship to the basin of said mold when the holder is moved to its discharging position.

8. In mechanism of the class described, the combination of a support, a holder adapted to receive metal trunnioned on said support, said holder having a side wall which is shaped for co-operation with other walls of the holder to hold the metal when the holder is tilted on its trunnions, and formed with a discharge opening which is arranged above the level of the metal when the holder is in normal position but is moved to a position below such level when said holder is tilted, and means for limiting the tilting of said holder in one direction at a predetermined position.

9. In apparatus of the character described, the combination with a mold having a pouring basin, of a support, a metal holder provided with a discharge port for the metal and trunnioned on said support to move from a normal position to a discharging position, an upwardly extending member disposed in a vertical plane coincident with the plane in which the discharge port moves to direct the metal downwardly during tilting movement of said holder from normal position to its discharging position.

10. In apparatus of the character described, the combination with a mold having a pouring basin, of a support, a metal holder provided with a discharge port for the metal and trunnioned on said support to move from a normal position to a discharging position, an upwardly extending member carried by said support and disposed in a vertical plane coincident with the plane in which the discharge port moves to direct the metal downwardly during tilting movement of said holder from normal position to its discharging position.

11. In mechanism of the class described, the combination of a support provided with pairs of rollers, a holder adapted to receive metal, and trunnions on said holder arranged to engage said rollers, said holder having a side wall which is shaped for co-operation

- with other walls of the holder to hold the metal when the holder is tilted on its trunnions, and formed with a discharge opening which is arranged above the level of the metal when the holder is in normal position but is moved to a position below such level when said holder is tilted. 5
12. In mechanism of the class described, the combination of a support, a metal holder 10 trunnioned thereon and adapted to occupy a metal filling position and a metal discharging position and constructed and arranged to hold the metal when in either position, that side wall which forms the bottom of the 15 holder when moved to the discharging position being formed with a discharge opening disposed above the level of the metal when the holder is filled and is in the filling position and disposed at the lowest part of 20 said holder when the latter is in the discharging position, and means tending to maintain the holder in the filling position or to return it thereto when moved to the discharging position. 25
13. In mechanism of the class described, the combination of a support, a metal holder trunnioned thereon and adapted to occupy a metal filling position and a metal discharging position and constructed and arranged 30 to hold the metal when in either position, that side wall which forms the bottom of the holder when moved to the discharging position being formed with a discharge opening disposed above the level of the metal 35 when the holder is filled and is in the filling position and disposed at the lowest part of said holder when the latter is in the discharging position, means tending to maintain the holder in the filling position or to return it thereto when moved to the discharging position, and means for locking the 40 holder in the discharging position. 45
14. In mechanism of the class described, the combination of a support provided with 50 pairs of rollers, a holder for receiving metal having in its wall a discharge opening arranged above the level of the metal when the holder is in normal position, said holder being provided with trunnions which rotatably bear on said rollers, whereby the holder can be tilted to arrange the discharge opening below the level of the metal for discharging the latter, and means engaging with one of said rollers of one pair thereof 55 for limiting the swinging of said holder in one direction. 60
15. In mechanism of the class described, the combination of a support provided with pairs of rollers, a metal holder having in its wall a discharge opening arranged above the level of the metal when the holder is in normal position, said holder being provided with trunnions which rotatably bear on said rollers, whereby the holder can be tilted to 65 arrange the discharge opening below the level of the metal for discharging the latter, and means arranged to engage certain of said rollers for limiting the swinging of said holder in either direction. 70
16. In mechanism of the class described, the combination of a frame having supporting devices, a holder for metal trunnioned on said devices, said holder being movable to a predetermined position to permit discharge of the metal through an opening 75 formed in its side wall, and means for adjusting each supporting device independently of the other device to position the holder horizontally. 80
17. In mechanism of the class described, the combination of a support, a pair of members adjustably mounted on said support, a metal holder having in its wall an opening arranged above the level of the metal when the holder is in normal position, trunnions 85 between said holder and the adjustable members, whereby the holder can be tilted to arrange the discharge opening below the level of the metal for discharging the latter, and means interposed between said holder and one of said adjustable members for limiting the tilting of the holder in one direction. 90
18. In apparatus of the class described, the combination of a support, a holder for metal trunnioned on said support, one wall 95 of said holder being formed with a discharge opening arranged to discharge metal when the holder is swung on its trunnions, and gravity controlled means for locking said holder in tilted position. 100
19. In mechanism of the class described, the combination of a support, a pair of adjustable members mounted on said support, a metal holder having in its side wall a discharge opening arranged above the level of the metal when said holder is in normal position, trunnions for supporting said holder on said adjustable members and permitting the holder to be rocked to position the discharge opening below the level of the metal, and means interposed between one 105 of said adjustable members and the holder for locking the holder in tilted position. 110
20. In mechanism of the class described, the combination of a support, a pair of adjustable members mounted on said support, a metal holder having in its wall a discharge opening arranged above the level of the metal when the said holder is in normal position, trunnions for supporting said holder 115 on said adjustable members, a locking member connected to said holder, and an element pivoted on one of said adjustable members and arranged to engage said locking member to lock the holder in tilting position. 120
21. In apparatus of the class described, the combination of a support, a metal holder having side walls of curvilinear shape, the free edges of which are correlated to form 125 an opening through which the holder is 130

filled, said holder being trunnioned on an axis coincident with its longitudinal axis and one side wall of said holder being formed with a discharge opening disposed between 5 the adjacent free edge thereof and the level of the metal when the holder is in normal position but arranged below that level when the holder is tilted on its trunnions.

22. In apparatus of the class described, 10 the combination of a support, a metal holder having side walls of curvilinear shape, the free edges of which are correlated to form an opening through which the holder is filled, said holder being trunnioned on an 15 axis coincident with its longitudinal axis and its said side wall being formed with a discharge opening disposed between the adjacent free edge thereof and the level of the metal when the holder is in normal position 20 but arranged below that level when the holder is tilted on its trunnions, and means for adjusting each trunnion for said holder on said support.

23. In apparatus of the class described, 25 the combination of a support, a metal holder having side walls of curvilinear shape, the free edges of which are correlated to form an opening through which the holder is filled, said holder being trunnioned on an 30 axis coincident with its longitudinal axis and its said side wall being formed with a discharge opening disposed between the adjacent free edge thereof and the level of the metal when the holder is in normal position 35 but arranged below that level when the holder is tilted on its trunnion, means for tilting said holder, and means for adjusting each trunnion for said holder on said support.

40 24. In mechanism of the class described, the combination with a mold, of a metal holder, a support on which said holder is pivoted to permit discharge of the metal therefrom, into the basin of said mold, and 45 an intermediate holder formed with a discharge opening in its bottom interposed between said holder and the basin of said mold, said intermediate holder permitting the metal to rise and accumulate therein 50 while flowing to the mold basin.

25. In mechanism of the class described, 55 the combination with a mold, of a support, a metal holder trunnioned on said support and adapted to be arranged in a non-discharging position and a discharging position, said holder being formed in its side wall with a discharge opening which is arranged above the level of the metal when the holder is in the non-discharging position 60 and is arranged below the surface of the metal when the holder is in the discharging position, and a metal receiving device formed with a discharge opening in its bottom and arranged between said holder and 65 the basin of said mold and constructed and

arranged to permit the metal to rise and accumulate therein while flowing to the mold basin.

26. In mechanism of the class described, the combination with a mold, of a support, 70 a holder for metal trunnioned on said support and having in its wall a discharge opening which is arranged above the level of the metal when the holder is in normal position, and is arranged below the level of the 75 metal when the holder is rotated on its trunnions, said support being constructed and arranged to support said holder in pouring relationship to the basin of said mold, and means interposed between said holder and 80 the mold basin for controlling the flow of metal from the discharge opening to the mold basin, said controlling means including a wall for guiding the flow of the metal to said means during the tilting movement 85 of said holder.

27. In mechanism of the class described, the combination with a mold, of a support, a metal holder trunnioned on said support and having in its wall a discharge opening 90 arranged above the level of the metal when the holder is in normal position, but arranged below the level of the metal when said holder is tilted on its trunnions, and a receiver interposed between said holder and 95 the basin of said mold and formed in its bottom with a discharge opening through which the metal flows to the mold basin, said receiver permitting the metal to collect therein while flowing to the mold basin. 100

28. In mechanism of the class described, the combination with a mold, of a support, a metal holder trunnioned on said support and having in its wall a discharge opening arranged above the level of the metal when 105 the holder is in normal position, but arranged below the level of the metal when said holder is tilted on its trunnions, a receiver interposed between said holder and the basin of said mold and formed in 110 its bottom with a discharge opening through which the metal flows to the mold basin, said receiver permitting the metal to collect therein while flowing to the mold basin, and means for directing the metal that is discharged from the opening of the holder during tilting movement thereof downwardly into said receiver. 115

29. In mechanism of the class described, the combination with a mold basin, of a 120 member for receiving metal and permitting it to collect therein, whereby foreign matter and slag will rise to its upper surface, said receiver being provided with a discharge opening in its bottom through which the 125 metal flows to said mold basin, and means arranged above said receiver for discharging metal thereinto.

30. In mechanism of the class described, the combination with a mold basin, of a 130

member for receiving metal and permitting it to collect therein whereby foreign matter and slag will rise to its upper surface, said receiver being provided with a discharge opening in its bottom through which the metal flows to said mold basin, and a holder for metal arranged above said receiver and provided with means for discharging the metal into said receiver at a point below the upper level of the metal in said holder.

31. In mechanism of the class described, the combination with a mold basin, of a support, a member for receiving metal and permitting it to collect therein, whereby foreign matter and slag will rise to its upper surface, said receiving member being provided with a discharge opening in its bottom through which the metal flows to said mold basin, and a holder trunnioned on said support above said receiving member and provided with means for discharging the metal from said holder to said receiving member when said holder is tilted on its trunnions.

32. The process of pouring metal which consists in discharging the metal from a holder at a point below its upper surface, then collecting the metal in a receiver to permit foreign matter and slag to rise to the surface of the metal in said receiver, then discharging the metal from the bottom of the receiver, then collecting the metal in a basin and causing it to collect therein to permit slag and foreign matter to rise to its upper surface, and finally discharging the metal from the basin at a point below its upper surface.

33. In apparatus of the class described, the combination with a mold, of means for discharging metal into the cavity of said mold, said means comprising a holder and a plurality of receivers disposed in different horizontal planes, each of said receivers being arranged to hold the metal to permit the slag and foreign matter to rise to the surface of the metal and formed with an opening in its bottom portion to discharge the metal at a point below its upper surface.

34. In apparatus of the class described, the combination with a mold, of a support and means for discharging metal into the cavity of the mold, said means comprising a plurality of holders arranged in different horizontal planes, each of said holders serving to hold the metal to permit the slag and foreign matter to rise to the top of the metal and being formed in its bottom with an opening to discharge the metal at a point below its upper surface, the uppermost holder being pivotally mounted on said support, whereby it can be moved to position its discharge opening above the surface of the metal therein.

35. In apparatus of the class described, the combination with a support and a mold, of a receiving member mounted on the sup-

port and having a discharge opening in its bottom for discharging metal into the cavity of the mold, and a holder trunnioned on said support and having in its wall a discharge opening arranged above the level of the metal when the holder is in normal position but is arranged below the level of the metal when the holder is tilted to discharge the metal into said receiving member, said receiving member having an upwardly extending portion to direct downwardly the metal discharged from said holder while being tilted.

36. In apparatus of the class described, the combination with a support and a mold, of means for discharging metal into the cavity of the mold, said means including a metal holder, guide members slidably engaging said support, and means operatively connected with said guide members for indicating when said holder has received a predetermined quantity of metal.

37. In apparatus of the class described, the combination with a support and a mold, of means for discharging metal into the cavity of said mold, said means including a metal holder, guide members slidably engaging said support, and means operatively connected with said guide members for indicating when said holder has received a predetermined quantity of metal and has discharged a predetermined quantity of metal.

38. In apparatus of the class described, the combination with a support and a mold, of means, including a holder for the metal, for discharging metal into the cavity of said mold, guide members slidably engaging said support, and means engaging said guide members and controlled by the weight of the metal in said holder for indicating when said holder has received or discharged a predetermined quantity of metal.

39. In apparatus of the character described, the combination with a support and a mold, of means for discharging metal into the cavity of said mold, said means including a holder for the metal, devices slidably engaging said support for movably supporting said holder thereon, and means engaging with said devices and controlled by the weight of the metal in said holder, for indicating when said holder has received or discharged predetermined quantity of metal devices for movably supporting said holder on said support.

40. In apparatus of the character described, the combination with a support and a mold, of means for discharging metal into the cavity of said mold, said means including a metal holder movably mounted on said support, means engaging with said holder and controlled by the weight of the metal therein, for indicating when said holder has received or discharged a predetermined quan-

ity of metal, and adjustable means interposed between said holder and said indicating means.

41. In apparatus of the class described, 5 the combination with a frame, of a pair of supports slidably mounted on said frame, means for discharging metal into a mold cavity, said means including a metal holder pivotally mounted on said supports, a pair 10 of levers pivotally mounted on said frame and operatively connected with said supports, and a weight to control the movement of said levers.

42. In apparatus of the class described, 15 the combination with a frame, of means for discharging metal into a mold cavity, said means including a metal holder, a pair of levers pivotally mounted on said frame and operatively connected with the opposite ends 20 of said holder, the connections between said levers and the opposite ends of said holder being adjustable, and a weight to control the movement of said levers.

43. In apparatus of the class described, 25 the combination with a frame, of means for discharging metal into a mold cavity, said means including a metal holder, a pair of levers pivotally mounted on said frame, means interposed between the opposite ends 30 of said holder and corresponding ends of said levers for supporting said holder thereon and permitting the holder to tilt, and a weight to control the movement of said levers.

35 44. In apparatus of the class described, the combination with a frame, of a pair of plates slidably mounted on said frame, means for discharging metal into a mold cavity, said means including a metal holder mounted on 40 said plates, a pair of levers mounted on said plates to support them, and a weight to control the movement of said levers.

45 45. In apparatus of the class described, the combination with a frame, of a pair of plates slidably mounted on said frame, means for discharging metal into a mold cavity, said means including a metal holder mounted on 50 said plates, a pair of levers mounted on said frame and operatively connected with said plates to support them, the connections between said levers and said plates being adjustable, and a weight to control the movement of said levers.

55 46. In apparatus of the class described, the combination of a support, a metal holder trunnioned at its opposite ends on said support, and movable from a normal position to a discharging position, said holder having 60 a discharge opening in its side wall arranged above the level of the metal in said holder when the latter is in normal position but arranged below the level of the metal when said holder is tilted, and a receiver 65 mounted on and extending transversely

across said support below and in the plane of movement of the discharge opening in its bottom, said receiver being formed with an opening through which the metal flows to the cavity of a mold.

70

47. In apparatus of the class described, the combination of a support, a metal holder trunnioned at its opposite ends on said support, and movable from a normal position to a discharging position, said holder having 75 a discharge opening in its side wall arranged above the level of the metal in said holder when the latter is in normal position but arranged below the level of the metal when said holder is tilted, a receiver 80 mounted on and extending transversely across said support below and in the plane of movement of the discharge opening in its bottom, said receiver being formed with an opening through which the metal flows to 85 the cavity of a mold, and means for controlling the movement of said holder.

85

48. In apparatus of the class described, the combination with a frame, of means for holding and discharging metal into the 90 cavity of a mold, sets of wheels for said frame, and means for causing relative movement between one of said sets of wheels and the frame, whereby the latter can be supported by either set.

95

49. In apparatus of the class described, the combination with a frame, of means for holding and discharging metal into the cavity of a mold, sets of wheels for said frame having their axes arranged at angles 100 to each other, and means for causing relative movement between one of said sets of wheels and the frame, whereby the latter can be supported by either set.

100

50. In apparatus of the class described, 105 the combination with a frame, including spaced supporting members provided with wheels permitting the frame to be positioned over a mold with the supporting member at either side thereof, of means on said frame for holding and discharging metal into the cavity of the mold, a separate set of wheels, and means for moving the separate set of wheels downwardly into engagement with the floor and through them elevating the 110 frame to support it on said separate set of wheels.

110

51. In apparatus of the class described, the combination with a frame including spaced supporting members provided with 120 wheels permitting the frame to be positioned over a mold with the supporting members at either side thereof, of means on said frame for holding and discharging metal into the cavity of the mold, a separate set of wheels, and means for moving the separate set of wheels downwardly into engagement with the floor and through them elevating the frame to support it on said separate set of wheels, said moving means being con- 125

130

structed and arranged to lock the frame in elevated position.

52. In apparatus of the class described, the combination with a frame including spaced supporting members provided with wheels permitting the frame to be positioned over a mold with the supporting members at either side thereof, of means on said frame for holding and discharging metal into the 10 cavity of the mold, a separate set of wheels slidably supported by said supporting members and mounted on axes arranged at an angle to the axes of the first mentioned wheels, and means for moving the said 15 separate wheels downwardly into engagement with the floor and through them elevate the frame to support it on said separate set of wheels.

53. In apparatus of the class described, 20 the combination with a frame including spaced supporting members provided with wheels permitting the frame to be positioned over a mold with the supporting members at either side thereof, of means on said frame 25 for holding and discharging metal into the cavity of the mold, a separate set of wheels slidably supported by said supporting members and mounted on axes arranged at an angle to the axes of the first mentioned 30 wheels, and means carried by each supporting member and arranged to move the adjacent separate wheel or wheels downwardly into engagement with the floor and through it or them elevate the frame to support the 35 latter on said separate wheel or wheels.

54. In apparatus of the class described, the combination of a frame having a pair of spaced supporting members mounted on 40 wheels, metal pouring mechanism mounted on said frame, a separate set of wheels each carried by a member slidably supported by one of said supporting members, a shaft mounted in bearings on each supporting member, and connections between each shaft 45 and the adjacent slidable members for lowering and raising it.

55. In apparatus of the class described, the combination of a frame having a pair of spaced supporting members mounted on 50 wheels, metal pouring mechanism mounted on said frame, a separate set of wheels each carried by a member slidably supported by one of said supporting members, a shaft mounted in bearings on each supporting member, and connections between each shaft 55 and the adjacent slidable member for lowering and raising it, said connections operating to maintain the slidable member in either position to which it is moved.

60. 56. In apparatus of the class described, the combination of a frame having spaced upright members adapted to be positioned at either side of a mold, a metal holder formed with a discharge opening and truncated 65 on said frame above the mold,

whereby it can be operated to position the discharge opening below the surface of the metal, a receiver arranged below said holder in position to receive metal therefrom and formed with an opening for discharging the metal into the mold, and a shield mounted on said frame in front of said holder and formed with an opening opposite said receiver and the discharge opening in said holder to permit a view of the metal as it 75 flows from said holder.

57. The process of pouring metal which consists in filling a ladle with a quantity of molten metal and permitting slag, foreign matter and impurities to collect on the surface of the metal, moving the ladle to discharge the metal from a point below its upper surface, collecting the metal in a receiver disposed beneath the ladle and permitting slag, foreign matter and impurities 80 to rise to the surface of the metal in the receiver, discharging the metal from the receiver through its bottom into a basin beneath the receiver, and collecting the molten metal in the basin to permit slag, foreign 85 matter and impurities to rise to the upper surface thereof, and finally discharging the metal from the basin at a point below its upper surface.

58. The process of pouring metal which 90 consists in filling a ladle with a quantity of molten metal and permitting slag, foreign matter and impurities to collect on the surface of the metal, operating the ladle to discharge the metal from a point below its 95 upper surface, collecting the metal in a receiver disposed beneath the ladle and permitting slag, foreign matter and impurities to rise to the surface of the metal in the receiver, discharging the metal from the receiver at a point below its upper surface 100 into a basin beneath the receiver, temporarily causing the molten metal to collect in a mold basin to permit slag, foreign 105 matter and impurities to rise therein by providing in the discharge for the basin a fusible gate which has a melting point below the temperature of the molten metal, whereby the molten metal will fuse the gate after rising in the basin and be discharged 110 through the discharge therefor.

59. The herein disclosed process of pouring metal into a mold cavity which consists in successively discharging the metal from the lowest portion of one vessel to another 120 vessel of a series of vessels arranged in different positions vertically and simultaneously and temporarily collecting the metal in each vessel while it is filling and the metal is discharging therefrom to the next lower vessel, whereby the slag and other impurities are collected on the surface of the metal and are the last to flow into the mold basin.

60. The process of pouring metal into mold cavities which consists in successively 130

collecting it in a series of vessels arranged in different positions vertically, discharging it from each of said vessels from a point below the surface of the metal, whereby the slag, foreign matter and impurities are collected and eliminated from the mold cavities, and temporarily causing the molten metal to collect in the last vessel by providing in the discharge therefor a fusible

gate which has a melting point below the 10 temperature of the molten metal, whereby the molten metal will fuse the gate after rising in the vessel and be discharged through the discharge therefor.

In testimony whereof, we have hereunto 15 signed our names.

DANIEL J. RYAN.
LOUIS J. FELTES.
